United States Patent Office

Des. 215,326

Patented Sept. 23, 1969

215,326

POCKET WATCH OR THE LIKE

Mel Appel, Short Hills, N.J., assignor to General Time Corporation, Stamford, Conn., a corporation of Connecticut

Filed Apr. 14, 1967, Ser. No. 6,706

Term of patent 14 years

Int. Cl. D10—02

U.S. Cl. D42—8

FIG. 2

FIG. 1

FIG. 3

FIG. 4

FIG. 7

FIG. 5

FIG. 6

FIG. 8

FIG. 1 is a front elevational view of a pocket watch or the like showing my new design in open condition;
FIG. 2 is a top plan view thereof;
FIG. 3 is an edge elevational view thereof;
FIG. 4 is a bottom plan view thereof;
FIG. 5 is a rear elevational view thereof;
FIG. 6 is an elevational view in closed condition;
FIG. 7 is a top plan view thereof; and
FIG. 8 is a bottom plan view thereof.

The essential features of the design are shown in full lines.

I claim:

The ornamental design for a pocket watch or the like, substantially as shown and described.
